(57) **CLAIM**

The ornamental design for a planter, as shown and described.

DESCRIPTION

FIG. 1 is a perspective view of the planter of the present invention;

FIG. 2 is a right side elevation view thereof;

FIG. 3 is a front elevation view thereof;

FIG. 4 is a top plan view thereof;

FIG. 5 is a rear elevation view thereof; and,

FIG. 6 is a second top plan view thereof shown.

The evenly-spaced broken lines depict environmental subject matter only and the unevenly-spaced broken lines depict the boundaries of the claim. Neither type of broken line forms any part of the claimed design.
